US00D631875S

(12) **United States Design Patent**
Skull et al.

(10) **Patent No.:** US D631,875 S
(45) **Date of Patent:** ** Feb. 1, 2011

(54) **MOUNT FOR ELECTRONIC DISPLAY**

(75) Inventors: **Joseph Skull**, Fridley, MN (US); **Joe Bures**, Columbia Heights, MN (US); **Robert Hagen**, Minneapolis, MN (US)

(73) Assignee: **Milestone AV Technologies LLC**, Savage, MN (US)

(**) Term: **14 Years**

(21) Appl. No.: **29/366,584**

(22) Filed: **Jul. 27, 2010**

(57) **CLAIM**

The ornamental design for a mount for electronic display, as shown and described.

DESCRIPTION

FIG. 1 is a front perspective view of a mount for electronic display according to the invention;

FIG. 2 is a front elevation view of the mount for electronic display depicted in FIG. 1;

FIG. 3 is a right side elevation view of the mount for electronic display depicted in FIG. 1;

FIG. 4 is a left side elevation view of the mount for electronic display depicted in FIG. 1;

FIG. 5 is a top plan view of the mount for electronic display depicted in FIG. 1; and

FIG. 6 is a bottom plan view of the mount for electronic display depicted in FIG. 1.

The rear elevation of the mount depicted in FIGS. 1-6 is not claimed, and are hence is not depicted.
